Fig. 1

Fig. 2

Fig. 3

Fig. 4

FIG. 1 represents a front elevational view of an automobile hood speedometer, showing my new design.

FIG. 2 is a top view of the same.

FIG. 3 is a side view of the same.

FIG. 4 is a bottom view of the same.

The rear of the speedometer is substantially plain in appearance.

My design for an automobile hood speedometer is characterized by the trapezoidal-shaped base thereof. The fragmentary portion of an automobile hood shown in broken lines in FIG. 3 is for illustrative purposes only.

I claim:

The ornamental design for an automobile hood speedometer, substantially as shown and described.
